HIGH INTENSITY LAMP

Dan M. Andre, Skokie, Ill., assignor to Universal
Lamp Co., Inc., Chicago, Ill.

Filed Dec. 15, 1970, Ser. No. 26,518

Term of patent 14 years

Int. Cl. D26—05

U.S. Cl. D48—20

FIG. 1

FIG. 4

FIG. 3

FIG. 2

FIG. 5

FIG. 8

FIG. 6

FIG. 7

FIG. 1 is a perspective view of a high intensity lamp illustrating my new design;

FIG. 2 is a front elevational view of the high intensity lamp on an enlarged scale;

FIG. 3 is a side elevational view thereof;

FIG. 4 is a top plan view thereof;

FIG. 5 is a rear elevational view thereof;

FIG. 6 is a rear elevational view thereof with a hanger hook in place thereon;

FIG. 7 is a side elevational view of the lamp illustrated in FIG. 6;

FIG. 8 is a top plan view of the lamp illustrated in FIG. 6.

The spherical lamp shade is rotatable within its socket.

I claim:

The ornamental design for a high intensity lamp, substantially as shown and described.
